UNITED STATES PATENT OFFICE.

CHARLES W. ZIEGLER, OF PROVIDENCE, PENNSYLVANIA.

ALARM-LOCK.

SPECIFICATION forming part of Letters Patent No. 238,172, dated October 12, 1880.

Application filed August 2, 1880. (Model.)

To all whom it may concern:

Be it known that I, CHARLES W. ZIEGLER, residing at Providence, in the county of Lackawanna and State of Pennsylvania, and a citizen of the United States, have invented a new and useful Improvement in Alarms for Door Locks and Latches; and it consists in the construction and special combinations of parts thereof, as will be fully hereinafter described.

10 In the drawings, Figure 1 is a plan or top side view as inserted in a door. Figs. 2 and 3 represent detail construction of parts. Figs. 4 and 5 represent the actuating-shaft and its connections. Fig. 6 represents the inner end 15 of the locking-bolt and its case. Fig. 7 represents the actuating devices to give an alarm, and Fig. 8 represents such devices thrown out of connection with the alarm, and the locking-bolt can be operated without sounding an 20 alarm.

A represents the door edgewise, looking from the top, in which the locking and alarm device is secured; A' A', the common knobs by which the device is operated.

25 B is a slotted cylinder, of the length of the thickness of the door, having the open slot b on its side, and an internal or female screw-thread, b', cut in its inner diameter.

b'' b'' are the common plates attached to the 30 cylinder and upon each face of the door, to secure the device to the door.

C is the actuating-shaft, centrally located in the cylinder B, having tangs c or other appliances at each end, to which the knobs that operate the shaft are secured, and has a slot, c', 35 Figs. 4 and 5, cut entirely through its diameter and in the central portion of its length. This shaft is smooth on its outer periphery.

D is a projecting pusher having a neck, d, 40 that goes through slot b in cylinder B, and an annular thimble, d', that surrounds the shaft C, and over which shaft and within slot b it is forced to slide. The forward side, d'', of this projecting pusher is inclined.

45 E E are cylindrical screw-nuts, the center bore of which fits the outside diameter of shaft C, and have screw-threads e e upon their outer peripheries, that screw into the screw-threads b' on the inner side of cylinder B.

50 e' e' are screw-pins that go into holes in the nuts E, through the slot c in shaft C, and

screw into screw-threads in the opposite side of said nuts E. These nuts are screwed up to be against or near the circular thimble d of pusher D, and when in place are secured by 55 said screw-pins e', when they will revolve with shaft C, and thereby force the projecting pusher forward or back, as the shaft C may be turned one way or the other.

F is a bolt-cylinder, which is inserted in the 60 frame of the door A, on a line and in the same plane with the pusher D, and has on its inner diameter a guide or feather, f, projecting inwardly, and is held in its place by the flush face-plate f', that is screwed fast to the door. 65

G is the locking-bolt, its outer end fitting into and sliding freely within the inner diameter of cylinder F. The inner end of this bolt has an angular or inclined face, g, to meet the inclined face d'' of pusher D, as seen in Fig. 70 1, and a longitudinal groove, g', is also made therein to fit onto feather f in cylinder G, to prevent the bolt from revolving in the cylinder. The central part of the length of this locking-bolt is of less diameter than the ends, 75 and made so that a spiral spring, g'', around it will bear against a shoulder, g''', on the inner end of the bolt, and the other end of the spring bears against a nut, H, fixed in cylinder F, and through which nut the bolt G freely 80 slides, by which construction the bolt G will recede and become flush with the edge of the door when relieved from the pusher D.

The revolving shaft C extends through the door and through an alarm-bell known as 85 "Corbin's bell," and is connected with the alarm mechanism of said bell, of which it is unnecessary to describe further than it affects this invention. On said shaft C, within the bell I, are radially-projecting actuators J, that 90 are caused, by the revolution of the shaft C, to strike against a curved pusher-plate, J', that is attached to the arm of the striking-hammer I', with a returning-spring back of it, so that as the actuators J force the pusher back while 95 passing it in their revolution the spring will act to cause the hammer I' to strike the bell as soon as the pusher is relieved from force by the projecting actuators.

In order to have the shaft C revolve without making an alarm, a switch-lever, L, is pivoted at l within the bell-case, which has a 100

notch, l' , on its outer side to engage a lug, l'' , projecting upward upon the pusher-plate J' , and by lifting lever L out of the notch m in the base-plate of the bell and forcing it toward the lug l'' , and engaging with it and forcing the pusher-plate back, and the lever into notch m' , the pusher-plate will be out of the reach of the actuators J in their revolution with shaft C , and when so out of the way shaft C can be revolved without sounding the bell or giving an alarm.

In operating the lock to force the bolt G out to lock the door, turn the outside knob to the right, or the inside knob to the left. This movement revolves the cylindrical nuts E , forcing the pusher D , with its inclined face d' , against the inclined face g of the bolt G , and as the shaft C continues to revolve and pusher D advances against the incline of bolt G the bolt continues to be forced out horizontally until the outer end protrudes beyond the edge of the door, as seen in Fig. 1 in broken lines. Then the door is locked, and if the lever L is in notch m of the base-plate of the bell, the bolt G cannot be thrown back by revolving the shaft C by either of the knobs A' without the bell being struck in alarm that some one is trying to unlock the door, and at every turn of the shaft C five alarms will be given by the hammer on the bell; but when the switch-lever L is turned back to rest in notch m' of the

base-plate of the bell the locking-bolt G can be turned back and unlock the door without sounding an alarm. This construction of parts admits of setting the screw-nuts a little farther apart, so that by turning the shaft C , the actuators J will act to sound the bell without advancing pusher D , and so be used as an ordinary door-bell.

Having thus described my invention, what I claim is—

1. The combination of the slotted cylinder

B , with internal screw-thread, b' , revolving slotted shaft C , screw-nuts E , and inclined-faced projecting pusher D , with the sliding locking-bolt G , having the inclined face g , all constructed to operate as and for the purpose described.

2. In an alarm-lock for doors, the combination of the revolving slotted shaft C , pusher D , and bolt G with the actuators J , spring-pushers J' , hammer I' , and bell I , constructed to operate as described.

3. In a door locking and alarm device having a revolving shaft, C , and actuators J , the combination of the pivoted switch-lever L with the pusher J' and notch m' in base-plate of bell device, as and for the purposes described.

CHARLES W. ZIEGLER.
